UNITED STATES PATENT OFFICE.

RAYMOND E. SABIN, OF FLUSHING, NEW YORK.

EVAPORATOR FOR REFRIGERATION MACHINES.

Application filed November 18, 1926. Serial No. 149,262.

This invention relates to evaporators for use in connection with household refrigeration machines, for the purpose of evaporating liquefied refrigerant gas delivered from 5 a condenser, having reference especially to the type of evaporator operating with an expansion valve.

The object of my invention is to provide a simple, compact and reliable evaporator, 10 comprising a novel construction and arrangement of the chamber or chambers in which evaporation of the liquefied gas is efficiently accomplished, and also the unitary association of an evaporating chamber or 15 chambers with a tank or tanks in which the liquid or solution for heat absorption is contained.

The invention also comprises novel features of construction and combinations of 20 parts which will be hereinafter described and claimed.

In the drawings—

Figure 1 is a plan, partly in section, of an evaporator embodying my invention.

25 Fig. 2 is a front elevation thereof.

Fig. 3 is a transverse vertical section, as on the line 3—3 of Fig. 1.

Fig. 4 is a longitudinal vertical section, enlarged, of one of the evaporating chambers.

30 Referring to the drawings, A, B designate spaced-apart duplicate units, each comprising a tank 10 adapted to contain a liquid effective for heat absorption, as, for example, a solution of calcium or brine. The tank is 35 formed in a cast body of non-corrosive metal or alloy, which body is exteriorly flanged, as at 11, and has a rearward extension 12 supporting a vertical cylinder 13 constituting an evaporating chamber for liquefied refrigerant gas. This cylinder is composed of 40 a non-porous metal or alloy of higher melting point than that of the tank, and the tank is cast about the cylinder, the two elements thus being, in effect, an integral structure 45 with the tank and evaporating chamber in intimate thermal contact.

The cylinder 13 is provided at its respective ends with flanged gas tight heads 14 which are welded, brazed, or otherwise secured in place. The upper head is provided 50 with an inlet 15 for liquefied refrigerant gas flowing from a suitable condenser, and the lower head is provided with an outlet 16 for the vapor. The cylinder is fitted with a succession of spaced-apart cup-like baffles 17 55 which are constructed and arranged to di-

rect the fluid in a devious course during its descent through the evaporating chamber. These baffles consist of metal diaphragms having up-standing peripheral flanges 18 60 which are in intimate thermal contact with the interior wall of the cylinder, so as to facilitate the flow of heat to the liquefied gas and vapor in their devious passage. The baffles are perforated and provided with 65 short overflow tubes 19 which rise to a plane slightly below the top of the flanges or side walls of the respective baffles, thus serving as overflow openings, or traps, which separate from the liquid contained in the respective baffles any foreign matter that may have been accidentally admitted to the gas system, thus preventing the entrainment of such matter with the vapor. The overflow openings of the successive baffles are arranged in staggered relation and are separated from each other as far as possible so as to ensure the distribution of the liquid and vapor throughout the chamber and expose 75 them to a succession of large metal evaporating areas during their devious passage from the top to the bottom of the evaporating chamber, thus facilitating heat transfer and promoting efficient evaporation.

The space above the top baffle 17 is preferably of ample size to receive a fabric bag containing a quantity of suitable dehydrating material, if desired.

The two units, A, B, each comprising an integral solution tank and an evaporating chamber, are supported in spaced relation by means of a suitable case, consisting, preferably, of a U-shaped metal structure 20 which embraces the two units so as to enclose the two tanks of their cylinders. The forward, upper and lower edges of the structure have formed thereon or secured thereto longitudinal angle strips 20' which provide tongues or flanges to receive and support the crimped or folded longitudinal edges of a 95 sheet-metal face plate 21'. This plate has a suitable opening therein to permit ready access to the chamber or compartment formed between the two units.

In the present instance, the evaporating 105 chambers are intercommunicably connected in series, that is, the supply pipe 21 from a condenser enters the inlet 15 of the evaporating chamber of the unit A; a pipe 22 connects the outlet 16 of said chamber with the 110 inlet 15 of the evaporating chamber of the unit B, and the outlet of the latter chamber

is connected with the usual receiver of the refrigerating system by means of a discharge pipe 23. The supply pipe 21 from the condenser is equipped with any usual or approved form of expansion valve 24, which is located within the compartment between the two units and thereby protected; the top of the case being provided with a suitably located opening 25 through which adjustment of the valve can be readily effected, as occasion may require.

A pan or vessel 26 containing the substance to be frozen is supported in the compartment, the lateral flanges 11 on the inner sides of the tank bodies presenting convenient ledges for the support of the receptacle, as indicated in dotted lines in Figs. 1 and 2.

I have herein shown and described an apparatus having two of my novel evaporating units connected in series, but it is obvious that they may be connected in parallel, series or series-parallel, and that in any case a greater number of units may be employed where a plant of larger capacity is required.

It is to be understood that my invention is not limited to the particular construction and arrangement described, as the same may be modified within the principle of my invention and the scope of the appended claims.

I claim—

1. An evaporator unit for refrigeration machines, comprising a cast metal tank for heat absorbing liquid and a hollow structure about which the tank is cast, said structure being of higher melting metal than the tank, and constituting an evaporating chamber having a non-porous wall in intimate thermal contact with the tank.

2. An evaporator for refrigeration machines, comprising a plurality of units, each embodying a tank for heat absorbing liquid and an evaporating chamber, a casing enclosing said units and supporting them in spaced relation so as to provide a compartment therebetween, means intercommunicably connecting the plural chambers, and an expansion valve in the liquid supply connection to the chambers, said valve being located in the compartment.

3. An evaporator for refrigeration machines, comprising a plurality of units, each embodying a tank for heat absorbing liquid and an evaporating chamber, a casing enclosing said units and supporting them in spaced relation so as to provide a compartment therebetween, said casing comprising a U-shaped structure embracing the units, and a face plate having an opening therein at the front of the compartment, means intercommunicably connecting the plural chambers, and an expansion valve in the liquid supply connection to the chambers, said valve being located in the compartment.

4. An evaporator for refrigeration machines, comprising a plurality of units, each embodying a tank for heat absorbing liquid and an evaporating chamber, a casing enclosing said units and supporting them in spaced relation so as to provide a compartment therebetween, means intercommunicably connecting the plural chambers in series, and an expansion valve in the liquid supply connection to the chambers.

Signed at New York in the county and State of New York this 9th day of November A. D. 1926.

RAYMOND E. SABIN.
